UNITED STATES PATENT OFFICE.

GEORGE E. BLAKE, OF SPRINGFIELD, MASSACHUSETTS, AND JOHN H. BRUNINGA, OF ST. LOUIS, MISSOURI, ASSIGNEES, BY MESNE ASSIGNMENTS, TO HENRY HYMAN, OF NEW YORK, N. Y.

SPOTLIGHT.

Application filed November 11, 1922. Serial No. 600,272.

This invention relates to battery hand lamps, and more particularly to battery hand lamps of that type in which the beam is arranged to be concentrated or spread at pleasure.

In battery hand lamps, the spreading and concentrating of the beam is accomplished by relative movement of the reflector and the lamp, the reflector being so constructed that when there is a relative movement of the lamp and the reflector along the axis thereof, the distribution of the light will be varied to either project a closely focused beam or project a spreading beam. To secure such action, it is necessary that the movable part be so guided as to always insure correct alinement in order that dark spaces and rings may be eliminated.

One of the objects of this invention, therefore, is to provide a battery hand lamp in which the reflector is so supported and guided for movement as to always keep in accurate alinement with the lamp in its various positions with respect thereto.

Another object of this invention is to provide a battery hand lamp in which the lamp itself will be so secured and fixed in the casing as to permit free adjustment of the reflector head on the casing and without interfering with the position of the lamp itself.

Another object of this invention is to provide a battery hand lamp in which the lamp support is so mounted in the casing, as to not only permit it to be readily detached therefrom, while at the same time providing a firm fixture when in place, but in which the connection between the switch and the lamp is such as to be always well made and to facilitate the making of the same when, after detachment, this support has been replaced.

Another object of this invention is to provide an extra lamp holder which is so combined with the spring as to form an assembled unit on the end cap closing the casing.

Further objects will appear from the detail description taken in connection with the accompanying drawing, in which:

Figure 1 is a longitudinal section of a battery hand lamp embodying this invention, the switch being shown in elevation; and

Figures 2 and 3 are enlarged views of Figure 1.

55

Referring to the accompanying drawing, 1 designates a battery-receiving casing which is, in this particular embodiment, made of metal, the casing being expanded and formed to provide threaded ends 2 and 3. This casing is arranged to receive a battery which, as usual, consists of a series of cells placed end to end in an insulating casing. The switch mechanism is in this particular embodiment of the construction shown and described in Patent No. 15,249, 60 reissued December 20, 1921, and comprises, generally stated, a casing 5 having a button 6 and a slider 7, this casing having a contact, one end of which is electrically connected with the casing 1 and which is arranged to engage a contact strip extending along but insulated from the casing and the switch by insulation 9.

65

70

Mounted in the upper end of the casing is 75 a lamp support comprising a metallic cup 10 having a downwardly extending flange or rim 11 and an insulating disc 12. Beaded on the insulating disc and projecting therethrough is a tubular metal structure embodying a threaded nipple 13 for receiving the lamp 14 and projecting above the support, while projecting below the support is an extension 15 which is closed by a cap 16 of insulating material on which the extension 80 is beaded. This cap of insulating material receives a socket 17 having an end 18 arranged to be engaged by the terminal of the battery. Sliding within this socket 17 is a plunger 19 which is forced toward the lamp 90 terminal by a spring 20, it being noted that the plunger and the socket have interengaging flanges to prevent total separation of the two parts. It will be seen that this construction provides a bunter on the support 95 for the battery while the spring pressed plunger provides a contact and a shock absorber.

95

The flange 11 is surrounded by a ring or sleeve 21 of insulating material, such as 100 fibre, and over which the insulating disc 12 also of fibre lies. It will be noted that the bottom of the extension 2 provides a shoulder 22 against which the sleeve 21 is arranged to take. However, in order to provide an accurate bearing, the sleeve is faced 105

with a liner 23 of metal. Accordingly the strip 8 is arranged to lie between the flange 11 and the sleeve, it being, however, noted that this strip as well as the lamp are entirely insulated from the casing and even from the liner 23. In order to secure the parts in place, there is provided a clamping ring or retainer 24 which is arranged to thread into the end 2 and is provided with a flange 25 bearing on the disc 12 to securely clamp the parts within the end 2 and with the liner 23 against the shoulder 22. In order to permit ready manipulation of the ring, it is struck up at various points as shown at 26 to provide lugs arranged to be engaged by the fingers.

The end 2 has threaded thereon the neck 27 of the reflector carrying head 28. This head receives a reflector 29 which rests on a ring 30 beaded on the head while on the reflector rests the lens 31; all of these parts are clamped together by a clamping ring 32 which is threaded on the reflector head and has a flange 33 taking over the lens. It will be noted that the reflector has a nipple 34 which, however, takes loosely over the lamp socket nipple 13 and thus is wholly out of contact therewith. It will be noted that the reflector and lens are firmly clamped in the head, while this head itself is mounted for adjustment on the end 2, the neck 27 being provided with a knurled rib 35 to permit ready adjustment.

The end cap 36 which is also of metal has a threaded flange 37 cooperating with the threaded end 3. This end cap carries the spring 38 which bears against and makes contact with the bottom of the battery 4 and holds the same against the bunter 18. This spring is mounted on a cover or closure 39, being secured thereto by struck-up portions 40 through which convolutions of the spring pass. This closure takes into a flanged cup 41 so as to provide a spare-lamp casing 45 which is fastened to a disc 42 of insulating material by a large tubular rivet 43 the disc of insulating material being sprung into a bead 44 on the cap, while the tubular rivet bears on the cap itself and thus electrically connects the cap and the casing with the spring 38. Mounted within the cup and the closure is a clip 45 which is also secured by a tubular rivet 43 and which is arranged to receive and carry a spare lamp 46.

Upon referring more particularly to Figures 1 and 2, it will be noted that the lamp is firmly supported in the casing so as to be fixed therein and with respect thereto, while the battery is firmly held against the bunter by the spring 38. The reflector head is, however, mounted for adjustment along the casing; accordingly by rotating the reflector the relative positions of the reflector and the lamp may be varied to either concentrate or spread the beam. In view of the fact that

the lamp is wholly supported within the casing and independent of the reflector, this adjustment can be readily accomplished, and by making a sufficiently tight joint between the end 2 and the neck 27, any adjustment will be readily retained. In following the circuit connections, it will be noted that the strip 8 is effectively insulated from the casing so as to make a connection with the outside terminal of the lamp, the connection of the inside terminal being through the plunger to the battery. It will further be noted that while the lamp support is firmly held in the casing, it will be readily removable therefrom in order to clear the casing, for by removing the clamping ring 24, the entire lamp support can be readily removed. This leaves the end of the casing entirely open so that if a battery does become stuck, as frequently happens, this battery can be pushed out of the end of the casing. It will be noted, however, that the strip 8 is straight and has no hooks; accordingly this strip will not interfere with the ejection or replacement of a battery. Furthermore the construction is such that the lamp support can readily be placed back in the casing as the end of the strip 8 will readily slip between the flange 11 and the insulating sleeve 21. It will be noted that the insulating sleeve 21 is faced with metal; this is necessary for the reason that insulating material varies in its dimensions in accordance with atmospheric conditions; however, by providing metal liners and facings, the desired accurate fit can readily be obtained with interchangeability of parts and quantity production.

Upon referring to Figure 3, it will be seen that there is provided an extra lamp holder which enables a defective lamp or broken lamp to be readily replaced. At the same time this lamp holder provides a convenient mounting for the spring. When it is desired to secure an extra lamp, the cap is removed and by then pulling the closure 39 from the cap 41, the lamp can be taken out of the clip.

It is obvious that various changes may be made in details of construction, within the scope of the appended claims, without departing from the spirit of this invention; it is, therefore, to be understood that this invention is not to be limited to the specific details shown and described.

Having thus described the invention, what is claimed is:

1. A battery hand lamp comprising, a battery receiving casing, an insulating ring fitting the lamp end of said casing, a support having a flange fitting said ring, a lamp in said support, and a contact strip between said flange and said ring.
2. A battery hand lamp comprising, a battery receiving casing, an insulating ring fitting the lamp end of said casing, a sup-

port having a flange fitting said ring and fixed in said casing, a lamp in said support, and means on said support adapted to receive the thrust of the battery and to yieldingly connect the battery with said lamp.

3. A battery hand lamp, comprising, a battery receiving casing having a shoulder spaced from the end thereof, an insulated lamp support resting against said shoulder, a lamp in said support, independent means engaging the inside of said casing adapted to clamp said support against said shoulder, and a circuit connection to said support.

4. A battery hand lamp, comprising, a battery receiving casing having a shoulder spaced from the end thereof, an insulated lamp support resting against said shoulder, a lamp in said support, a clamping ring engaging the inside of said casing adapted to clamp said support against said shoulder, and a circuit connection to said support.

5. A battery hand lamp, comprising, a battery receiving casing having a shoulder spaced from the end thereof, an insulated lamp support resting against said shoulder, a lamp in said support, independent means engaging the inside of said casing adapted to clamp said support against said shoulder, a contact rim on said support, and a circuit connection to said rim.

6. A battery hand lamp, comprising, a battery receiving casing having a shoulder spaced from the end thereof, an insulated lamp support resting against said shoulder, a lamp in said support, independent means engaging the inside of said casing adapted to clamp said support against said shoulder, means on said support adapted to receive the thrust of the battery and to yieldingly

connect the same with said lamp, and a circuit connection to said support.

7. A battery hand lamp comprising, a battery-receiving casing, a lamp support mounted in one end of said casing and abutting thereagainst, a reflector head mounted for adjustment on said end of said casing, and a clamping ring for securing said support in abutment with said casing.

8. A battery hand lamp comprising, a battery-receiving casing provided with a shoulder near one end, a lamp support mounted in said end and against said shoulder, a clamping ring for securing said support, and a reflector head mounted for adjustment on said end of said casing.

9. A battery hand lamp comprising, a metallic battery-receiving casing, a lamp support mounted in one end of said casing and having a contact flange, a removable retainer engaging said casing for securing said support, an insulating sleeve between said flange and said casing, and a circuit connection to said flange.

10. A battery hand lamp comprising, a metallic battery-receiving casing, a lamp support mounted in one end of said casing and having a contact flange, a removable retainer for securing said support, an insulating sleeve between and separating said flange and said casing, and a contact strip between said flange and said sleeve.

In testimony whereof I affix my signature this 18th day of September, 1922.

GEORGE E. BLAKE.

In testimony whereof I affix my signature this 8th day of September, 1922.

JOHN H. BRUNINGA.
